REED SWITCH ENVELOPE ASSEMBLY

Bernard Edward Shlesinger, Jr., 9411 Macklin Court,
Alexandria, Va. 22309

Filed July 27, 1972, Ser. No. 275,833

Term of patent 14 years

Int. Cl. D13—03

U.S. Cl. D26—13 R

Fig. 1

Fig. 2

Fig. 3

Fig. 4

Fig. 5

FIG. 1 is a side elevational view of a reed switch envelope assembly;

FIG. 2 is an end elevational view thereof;

FIG. 3 is a top plan view thereof;

FIG. 4 is a side elevational view of a modified form of the reed switch envelope assembly described in FIG. 1 showing my new design;

FIG. 5 is an end elevational view thereof.

The side opposite to the ends shown in FIGS. 2 and 5 are identical with these respective figures.

The bottom plan view opposite to the top plan view shown in FIG. 3 is identical with this figure.

The sides and bottom plan views of the reed switch envelope assembly shown in FIG. 4 are identical with this figure.

FIGS. 1, 3 and 4 are broken away to show indefinite length.

I claim:

The ornamental design for a reed switch envelope assembly, as shown and described.
